UNITED STATES PATENT OFFICE.

MICHAEL KIRNBAUER, OF FOREST PARK, ILLINOIS.

CULINARY SLICING MACHINE.

Application filed May 16, 1922. Serial No. 561,269.

To all whom it may concern:

Be it known that I, MICHAEL KIRNBAUER, a citizen of the Republic of Austria (who has declared his intention of becoming a 5 citizen of the United States of America), now residing at Forest Park, in the county of Cook and State of Illinois, have invented certain new and useful Improvements in Culinary Slicing Machines, of which the 10 following is a specification.

This invention relates to that class of culinary slicing machines in which a reciprocating holder or hopper has movement past a stationary cutter blade to effect a slicing of the articles operated on.

The present improvement has for its objects:—

To provide a structural formation and association of the holding hopper and weight- 20 ed follower by which the material to be sliced is fed towards the cutter blade, and in which the hopper is supported in a readily detachable manner and effectively guided in its rectilinear reciprocation.

To provide a structural arrangement whereby the weighted follower is guided vertically in the holding hopper, and is effectively maintained in an elevated position while it is swung to one side and above 30 the hopper to permit of a convenient introducing of the material into said hopper, and by means of which a descent of said follower below a predetermined distance above the cutter blade is prevented, all as will 35 hereinafter more fully appear.

In the accompanying drawings:

Fig. 1, is a perspective view illustrating the general arrangement of parts in the machine.

Fig. 2, is a central longitudinal sectional elevation.

Fig. 3, is a top view with parts broken away and in section.

Fig. 4, is an enlarged detail transverse section on line 4—4, Fig. 3, illustrating the track structure and adjustable slicing blade.

Fig. 5, is an enlarged detail horizontal section on line 5—5, Fig. 2, illustrating the detachable connection between the hopper 50 and its operating pitman.

Like reference numerals indicate like parts in the several views.

Referring to the drawings, 1 designates a flat plate constituting the base of the ma-

chine and provided with feed 2 by which it 55 is supported above a receiving dish or receptacle for the sliced material.

3 designates a transverse opening through the base 1 for the passage of the sliced material, and 4 designates a transversely ar- 60 ranged slicer blade arranged at a margin of said opening, and which is preferably of the adjustable type described in my prior Patent No. 1,415,449, dated May 9, 1922, and which as illustrated in Figs. 2 and 4 com- 65 prises a construction as follows:—

5 designates a rock shaft journaled near its respective ends in the base 1 and having at one end a bent arm 5' the end of which is formed with gear teeth for operative en- 70 gagement with the teeth of a worm hub 6 journaled in the base 1 and having at its upper end an operating head by which manual adjustment of the parts can be effected. In such construction the butt of the cutter 75 blade 4 is fixedly attached to the shaft 5 so as to be adjustable therewith.

7 designates a companion pair of track sections arranged at the respective sides of the base 1, and each comprising an open 80 sided shell or tube, rectangular in cross-section, with the open sides of the two shells in opposed relation. The track sections 7 are preferably held in place upon the base 1 by confining bars or rails 8 of wood or the 85 like.

9 designates the holding hopper, preferably of a rectangular form, and open at top and bottom.

10 designates trough shape members se- 90 cured to the opposite sides of the hopper 9 and near the lower end of the same. The bottom web of such members 10 are formed with openings for the passage of track wheels 11, the carrying axles of which are in 95 turn carried by the respective vertical webs or flanges of the track sections, as shown more particularly in Figs. 4 and 5. In the described construction the track wheels 11 have rolling bearing in the cavities of the 100 track sections 7, and owing to the open end formation of such track sections, a ready endwise removal of the hopper 9 and accessories for cleaning and repair can be effected.

12 designates an operating shaft mounted 105 transversely in bearings above the base 1 and provided at one end with a handled wheel 13 for manual operation; and near its mid-

length with a crank arm 14 connected by a pitman 15 with the hopper 9, so as to impart reciprocation thereto. The connection of the pitman 15 to the hopper 9 is preferably effected by a detachable connection as follows.

16 designates orificed pivot ears on the hopper 9, between which is arranged an orificed head on the adjacent end of the pitman 15.

17 designates a sliding pivot pin having movement in the aforesaid ears 16 and in an auxiliary ear 16' on the hopper, and adapted to form the pivotal connection between the pitman 15 and the ears 16.

18 designates a spring tending to force and hold the pin 17 in the above described engagement, and 19 designates a finger piece on an end of the pin 17 for the convenient 20 withdrawal of the same from the described engagement.

20 designates a bracket secured to the rear side of the hopper 9, and having horizontal upper flange providing a bearing for the 25 swinging cross head now to be described.

21 designates a cross head or bar pivoted near one end, and by means of a vertical pivot stud 22, in the horizontal flange of the bracket 20 aforesaid, while the forward or 30 swinging end of the cross head is adapted for engagement in an open or side notch in a hasp plate 23 secured to the front side of the hopper as shown in Figs. 1, 2 and 3.

24 designates a central guide sleeve or 35 hub on the cross-head 21 for guiding engagement with the guide stem of a weighted follower hereinafter described.

25 designates pivot ears arranged on the cross-head 21 at a point to the rear of the 40 pivot stud 22, to afford pivotal support for the lever of an automatic controlling means hereinafter described.

26 designates the weighted follower heretofore referred to, of a form corresponding 45 with the interior of the hopper 9 and having movement therein to press the material being sliced towards the slicer blade 4 of the machine.

27 designates a tubular stem extending up 50 from the follower 26 and having guiding engagement in the guide sleeve 24 of the cross-head 21 aforesaid, so as to have movement in a vertical plane only and without liability to a tilting movement under any irregularity 55 of the material operated on. In the preferred construction shown, the circular wall of the tubular stem 27 is formed with a vertical guide slot in which the side of a pulley hereinafter described, has bearing to hold 60 said stem and the weighted follower 26 from a turning movement, and at the same time permit of an entry of the flexible connection or cord hereinafter described.

28 designates the pulley above referred to, 65 journalled in brackets on the cross-head 21

and extending into the vertical slot of the stem 27 to provide guiding engagement therefor.

29 designates a flexible connection or cord passing over the pulley 28, down vertically 70 within the bore of the stem 27 and secured to the lower portion of said stem or an adjacent portion of the follower 26 carried by said stem. The other portion of the flexible connection 29 extends horizontally from the pulley 28 and is attached to a lever now to be described.

30 designates a lever or bar pivoted at one end to the aforesaid pivot ears 25 of the cross-head 21 and having connection with the flexible connection 29 at a distance from its fulcrum point as shown more particularly in Figs. 1 and 2.

31 designates a stop flange or rib on the cross-head 21, arranged in the path of the 85 lever 30 and adapted to stop and hold said lever and its connections from further movement when the associated weighted plunger 26 has reached a predetermined distance above the slicer blade 4, and in order to 90 avoid contact and injury to said parts. The above described construction provides manual means for raising the weighted follower 26 at a point above the top of the hopper 9 so that said follower along with the cross-head 21 and accessories may be swung to one side as illustrated in dotted lines in Fig. 1, to permit of the introduction of 95 material into the hopper 9, as well as in a disassembly of the parts for cleaning and 100 repair. In this connection a material feature of the invention involves a freedom to rearward movement in lever 30, so that the point of attachment of the flexible connection 29 to the lever can be brought to a 105 plane below the fulcrum point of the lever. With the parts in such rearward position, as illustrated in full lines in Fig. 2, any stress 110 on the part of the flexible connection will have no tendency to move the lever from its position, and it will be necessary to manually raise said lever to a plane above its fulcrum point, before the follower 26 and 115 associated parts are capable of downward movement by gravity.

Having thus fully described my invention, what I claim as new and desire to secure by Letters Patent, is:

1. In a slicing machine, the combination of a holding hopper open at top and bottom 120 and provided with a pivot bracket at one side, a follower moving in said hopper and having a guide stem, a horizontally swinging cross head pivoted at one end to the aforesaid bracket and having a guide for the 125 follower stem, a latch piece on the hopper having holding engagement with the swinging end of the cross head, and manual means on said cross head for effecting an upward movement of the follower.

2. In a slicing machine, the combination of a holding hopper open at top and bottom and provided with a pivot bracket at one side, a follower moving in said hopper and having a guide stem, a horizontally swinging cross head pivoted at one end to the aforesaid bracket and having a guide for the follower stem, a latch piece on the hopper having holding engagement with the 5 swinging end of the cross head, and manual means on said cross head for effecting an upward movement of the follower, the same comprising a lever pivoted on the cross head, a flexible connection and pulley intermediate of the lever and the guide stem of the follower, and a stop lug on the cross head 10 in the path of said lever.

10 15 20 25 30 35 40

3. In a slicing machine, the combination of a holding hopper open at top and bottom and provided with a pivot bracket at one side, a follower moving in said hopper and having a guide stem, a horizontally swinging cross head pivoted at one end to the aforesaid bracket and having a guide for

the follower stem, a latch piece on the hopper having a holding engagement with the 25 swinging end of the cross head, and manual means on said cross head for effecting an upward movement of the follower, the same comprising a lever pivoted on the cross head, a flexible connection and pulley intermediate 30 of the lever and the guide stem of the follower, and a stop lug on the cross head in the path of said lever.

4. In a slicing machine, the combination of a base having a transverse slicer blade 35 and guide tracks at its respective sides, said tracks having an open sided rectangular shell form open at both ends, a hopper open at top and bottom, trough shaped brackets on the sides of the hopper, track wheels carried by said brackets and having rolling movement in the tracks aforesaid, and means for imparting reciprocation to said hopper.

Signed at Chicago, Illinois, this 15th day of May 1922.

MICHAEL KIRNBAUER.
